By Daniel B. German

Attorney

UNITED STATES PATENT OFFICE.

HENRY ALBERG, OF OAKDALE, ILLINOIS.

TONGS.

Application filed November 12, 1926. Serial No. 147,991.

My invention relates to handling devices and more particularly to a pair of tongs for handling fire logs.

The principal object of the invention is to provide a pair of tongs which will facilitate the handling of fire logs and obviate burning and soiling of the hands incident to placing these logs in the fire-place.

A further object is to provide a pair of tongs which will effectively grip the log or other object, prevent tilting, is not cumbersome to handle, and is of simple and inexpensive construction.

Another object of the invention is to provide a device for handling irregularly shaped objects embodying a pair of coacting jaws for gripping the object therebetween and which will possess a maximum gripping or bearing surface thus insuring a positive grip.

In the accompanying drawings:

Figure 1 is a perspective of a pair of fire log tongs constructed in accordance with my invention;

Figure 2 is a vertical sectional view taken on line 2—2 of Figure 1; and

Figure 3 is a fragmentary perspective view of a modified embodiment of the invention.

Referring to the drawing in detail wherein the invention is illustrated, a pair of handles or levers are designated at 5 and which are provided with offset extensions 6 at their upper ends, the latter being arranged in crossed relation and pivotally connected together as at 7 and terminating in parallel hand loops 8. These handles or levers 5 are fashioned from suitable metal and have their outer ends cast with oppositely disposed longitudinally curved arms 9.

Transversely bowed sheet metal jaws 10 are provided for each arm 9 and are of such length as to conveniently grip and non-tiltingly hold a fire log or other similarly shaped object. These jaws 10 are arranged in opposed relation in the arms 9 conforming to their outer faces and riveted or otherwise secured to these arms as indicated at 11.

In order to hold the fire log against turn-

ing or vertical displacement or tilting when gripped by the jaws 10, the opposite longitudinal edges of each of the latter is bent at an oblique angle with respect to the vertical to afford divergent log engaging flanges or extensions 12 at their upper and lower edges. 55 Thus these flanges bear against the log at four spaced lines about its periphery and secure it firmly to support and balance the log against slipping or tilting.

In Figure 3 a modification of the invention is illustrated. In this instance the jaws and their handles are formed from an integral casting and the sheet metal jaws 10 are dispensed with. As shown this embodiment of the invention comprises an I shaped transversely bowed casting 13 to the upper end of which a lever or handle 14 is integrally and centrally attached. Log engaging flanges 12^a are also formed on these jaws or castings 13.

What I claim as new and desire to protect by Letters Patent of the United States is:

1. A pair of tongs comprising a pair of crossed pivoted handles, oppositely bowed coacting jaws carried thereby for gripping an object therebetween, and oppositely disposed lateral extensions carried by the upper and lower edges of the jaws and arranged to engage an object held between the jaws to hold the former against displacement.

2. A pair of tongs comprising a pair of crossed pivoted handles, oppositely curved extensions carried by the free ends thereof, transversely curved oppositely disposed jaws attached to the extensions, and lateral extensions extending longitudinally of the upper and lower edges of the jaws and adapted to engage an object held between the jaws to hold the former against vertical displacement and axial movement.

3. A pair of tongs comprising a pair of crossed pivoted handles, oppositely curved extensions carried by the free ends thereof, transversely curved oppositely disposed jaws attached to the extensions, and convergent extensions on the jaws at the upper and lower ends thereof and coacting to hold

an object against displacement when the jaws are in gripping engagement with an object.

4. A device of the character described including a pair of pivoted crossed handles, opposed transversely bowed jaws carried by the outer ends thereof, and marginal flanges

carried by the upper and lower ends of the jaws and projecting inwardly therefrom and arranged to bear against the object to coact with the jaws in holding the object. 10

In testimony whereof, I affix my signature at 10 South La Salle Street, Chicago, Ill.

HENRY ALBERG.
